UNITED STATES PATENT OFFICE.

FREEBORN F. RAYMOND, 2d, OF NEWTON, MASSACHUSETTS, ASSIGNOR, BY MESNE ASSIGNMENTS, TO THE MCKAY SHOE MACHINERY COMPANY, OF MAINE.

HEEL-COMPRESSING MACHINE.

SPECIFICATION forming part of Letters Patent No. 631,029, dated August 15, 1899.

Application filed January 18, 1897. Serial No. 619,573. (No model.)

To all whom it may concern:

Be it known that I, FREEBORN F. RAYMOND, 2d, a citizen of the United States, residing at Newton, in the county of Middlesex and State 5 of Massachusetts, have invented a new and useful Improvement in Heel-Compressing Machines, of which the following is a full, clear, and exact description, reference being had to the accompanying drawings, forming 10 a part of this specification, in explaining its nature.

The invention comprises a heel-compressing machine having opening and closing dies mounted upon the under surface of a stationary head or support, and a vertically-movable pressure-head below said first-named head, and a heel-seat former mounted upon said head to be horizontally movable thereon and also the breast-section of the die carried by 15 said movable pressure-head and horizontally movable upon it with the heel-seat former, the said pressure-head acting to move upward the heel-seat former and breast-section of the die to engage them with the die-sections carried upon the under surface of the 20 stationary head and with said head.

In the drawings, Figure 1 is a view in front elevation of a machine having the features of my invention. Fig. 2 is a view in vertical 25 central section upon the dotted line 2 2 of Fig. 1. Fig. 3 is a detail view, in vertical section, illustrating the position of the various parts of the die at the end of their compressing action. Fig. 4 is a vertical section of the 30 same parts, representing the position of the heel-seat former and breast-section of the die immediately after the compression of the heel-blank. Fig. 5 is a view, principally in inverted plan, of the side dies and the cross-head from the under surface of which they 35 are suspended. Fig. 6 is a view in horizontal section taken upon a line immediately above the heel-seat former and in plan below said line.

40 A is the base of the machine. From it extend upward rods a, preferably two on each side, and which are firmly united at their lower ends to the base and carry or support at their upper ends the stationary head B. 45 To the under surface of the stationary head

there is secured by cap-plates c slides C C', carrying die-sections D D', detachably secured to the slides. The slides have a closing and opening movement imparted to them by means of the links c¹ c², respectively, the 55 inner ends of which are pivoted to the outer ends of the slides, and the outer ends of which at c³ c⁴, respectively, are pivoted to ears or brackets c⁵ c⁶, extending from the sides of the vertically-movable pressure-head E. Each 60 slide may be connected with the said ear or bracket by one or by two links. The upward movement of the pressure-head E moves upward the brackets or ears and causes the links to be straightened, thereby moving the 65 slides C C' inward and closing the die-sections D D'. A downward movement of the pressure-head causes the links to be moved in a reverse direction and the slides to be moved apart, thereby separating the die-sections D D'. The pressure-head E is mounted upon the said rods a and is vertically movable by an eccentric upon the main shaft e and the eccentric-strap and connection e' with the pressure-head. (See Fig. 2.) The upper 70 part of the movable pressure-head E has horizontal guideways e², in which a plate or block F is movable horizontally from a position at the front of the machine (see Fig. 2) to a position beneath the die-sections D D', where it 75 is held stationary upon the pressure-head while the pressure-head is moved vertically to present it to the upperstationary head and to the die-sections D D'.

The block or plate F is represented as 80 moved horizontally on the pressure-head by the cam f on the cam-disk f', fastened to the main shaft, the cam being connected with the block or plate by the lever f², pivoted at f³ to the pressure-head E and having a short 85 arm connected with the upper end of the slide f⁴, the slide having at its lower end a cam-roll f⁵, which bears upon the cam. The long 90 arm of the lever f² is connected to the sliding block or plate F by means of a link f⁶. The 95 sliding block or plate carries the heel-seat former G, which is detachable from the plate, and it also has the breast-section H of the die, which has upon its outer face the inclined surface h, which inclined surface comes in 100

contact with the inclined surface h' on the inner side of a downward projection h^2 from the stationary head B. These inclines serve to close the breast-section of the die toward and upon the forward ends of the side sections of the die as the breast-section is moved upward, and the breast-section is of such height that at the end of its upward movement it laps or extends by the plate against which the bottom or tread end of the heel is compressed. (See Fig. 3.) The former G is supported upon the section f^7 of the said block F, the said section being large enough to hold the largest size of former which may be used. The former is represented as attached to this section by a pin which enters a hole therein, and is also represented as provided with a plane or straight front surface which abuts or bears against the inner surface of the breast-block H.

The heel-blank is represented as held upon the surface of the former G with its breast in contact with the inner face of the breast-block H by a holder M. This holder has a rounded or V-shaped surface to bear against the back of the heel-blank, and it has an outward yielding movement in respect to the inner face of the breast-block and also a downward movement, and it is also adjustable vertically. These features are provided in order that it may automatically adjust itself to heels of all sizes, and therefore hold upon the former heels of all sizes, and in order that it may be held stationary by the contact of its upper end with the side dies while the former is being moved upwardly, (see Fig. 3,) and also in order that its height may be varied in respect to the upper surface of the heel-seat former. I have therefore shown the holder at the upper end of a vertical arm m, which is pivoted at its lower end m' to the outer end of a horizontal arm m^2 , and this horizontal arm is in turn pivoted at its inner end m^3 to the under side of the block or plate F. A spring m^4 acts against the arm m^2 to lift it and hold it in its highest position, and a spring m^5 acts against the arm m to move the holder M toward the inner face of the breast-block and to hold it in such position. An adjusting-screw m^6 , which screws into and through a threaded hole in the arm m^2 , bears against the under surface of the block F and serves as a means for vertically adjusting the holder. The relation of the arms of the holder and of the holder to the heel-seat former and breast-block when an uncompressed heel-blank is held thereby is represented in Fig. 2. The position which the arms and the holder bear to these parts at the end of the compressing action is represented in Fig. 3.

The plate or block F, it will be observed, is used in connection with the former G and the breast-section H as a heel-blank feeding or transferring device to feed the heel-blank from a position at the front of the machine backward beneath the die-sections D D' and then upward between them, the said upward

movement causing the die-sections to be closed or brought together and the heel-blank compressed. The backward movement of the block F, former G, and breast-section leaves the compressed heel-blank held for an instant by the side dies D D', and the forward movement of the block or plate F removes these parts from beneath the die, so that an unobstructed space is provided for the escape of the compressed heel from the dies by gravity upon the incline N of the lower pressure-head, from which it slides into the trough or receptacle n. (See Fig. 2.) The compressed heel-blank may not readily leave the side dies D D' as they are opened, as it may adhere to the undersurface of the stationary pressure-head, and I have therefore represented an additional releasing device as provided by the plate O, movable in a guideway in the under surface of the pressure-head B, above the dies D D', the under surface of this plate forming the top of the die-cavity. This plate is made movable in relation to the side dies as the pressure-head is moved downward by means of a lever o, pivoted at o', the end o² of which engages a backward extension of the plate and the end o³ of which is connected with the movable pressure-head by the rod o⁴. There is provision for lost motion between the rod o⁴ and the pressure-head, whereby said rod o⁴ is not caused to be moved until the pressure-head has been moved downward nearly the full extent of its movement. This delays the movement of the plate O until the pressure-head has very nearly reached the end of its downward movement. It is closed upon the upward movement of the pressure-head and during the latter part of said movement. This is accomplished by the contact of the eye o⁵, through which the rod o⁴ extends, with a collar o⁶, adapted to slide a given distance upon said rod and acting against a spring o⁷, the eye coming into contact with the collar and moving upward the rod through the medium of the spring o⁷, thus closing or moving the plate O inward, but with a yielding stress. The outward movement of the plate from the dies D D' causes the dies to release the heel by the wiping action which takes place between them. I do not confine myself, however, to this particular means for freeing a heel-blank from the dies, and in such case the top of the die would be formed by a stationary plate attached to the under surface of the head B. A plunger actuated by a spring or by a lever connected with the moving part of the machine and movable downward from the head B into the die-cavity may be used for releasing the compressed heel therefrom.

Having thus fully described my invention, I claim and desire to secure by Letters Patent of the United States—

1. In a heel-compressing machine, the combination of a pressure-head B, separable sections of dies mounted upon the under surface thereof adapted to have closing and opening movements imparted to them, a heel-seat

former below said die-sections and means for moving said heel-seat former horizontally and vertically in relation to said separable die-sections.

5. 2. The combination of the pressure-head B, the slides C, C' mounted upon its under surface, the inverted die-sections D, D' carried by said slides against the under surface of the pressure-head and means for closing and opening said slides with the dies in their inverted position, as and for the purposes set forth.

3. The combination in a heel-compressing machine of the head B, the die-sections D, D' upon its under surface and means for closing and opening the same, the pressure-head E and the vertically-movable former G and breast-section H, as and for the purposes described.

4. The combination in a heel-compressing machine of the head B, the die-sections D, D' mounted thereon and means for closing and opening the same, a pressure-head, the heel-seat former G mounted thereon, the breast-section H of the die and the breast-section holder h^2 , as and for the purposes described.

5. The combination, in a heel-compressing machine, of the head B the die-sections D, D' thereon, adapted to have closing and opening movements imparted to them, the pressure-head E, the heel-seat former G, the breast-section H having the inclined surface h , the breast-section holder h^2 having the inclined surface h , all as and for the purposes set forth.

35. 6. The combination, in a heel-compressing machine of the head B, the die-sections D, D' provided with closing and opening movements thereon, the vertically-movable head E, the sliding block or plate F mounted thereon, the heel-seat former G carried thereby, and the breast-section H of the die also carried thereby, as and for the purposes described.

7. The combination, in a heel-compressing machine, of the head B, die-sections D, D' mounted on the under surface thereof having closing and opening movements, the vertically-movable pressure-head, the block or plate F horizontally movable thereon, the

heel-seat former G and the breast-section H carried thereby, the pressure-head being 50 formed to provide an escape passage or way for the compressed heel after the removal of the heel-seat former from the die-sections and outward movement thereof.

8. The combination of the pressure-head B, 55 the die-sections D, D' upon its under surface adapted to have closing and opening movements imparted to them, the heel-seat former and breast-section of the die horizontally and vertically movable as specified and means for 60 releasing the heel-blank from the die.

9. The combination in a heel-compressing machine of the pressure-head B, the side die-sections D, D' having closing and opening movements, and the plate O above said dies 65 and movable laterally in relation thereto, as and for the purposes specified.

10. The combination, in a heel-compressing machine of the pressure-head B, the side die-sections D, D' adapted to have closing and 70 opening movements imparted to them, the heel-seat former G, the breast-section H, both vertically movable, and the breast-section being adapted to extend beyond the upper surface of the die when in its highest position. 75

11. The combination, in a heel-compressing machine, of a holder for the breast of the heel, the heel-seat former and the holder M having yielding horizontal and vertical movements, 80 as and for the purposes described.

12. The combination, in a heel-compressing machine, of the heel-seat former G, the breast-section H and the holder M having the horizontal and vertical movements specified and means for adjusting the height thereof. 85

13. The combination, in a heel-compressing machine, of the heel-seat former G, the breast-gage and the holder M at the upper end of the arm m pivoted at m' to the arm m^2 , said arm m^2 pivoted at m^3 to the horizontally-mov- 90 able plate F and the springs m^5 and m^6 , as and for the purposes described.
